A. E. MOBERG

DOORSTOP

Filed Nov. 21, 1921

UNITED STATES PATENT OFFICE.

ARTHUR E. MOBERG, OF BATAVIA, ILLINOIS.

DOORSTOP.

Application filed November 21, 1921. Serial No. 516,679.

To all whom it may concern:

Be it known that I, ARTHUR E. MOBERG, a citizen of the United States, and a resident of Batavia, in the county of Kane and State 5 of Illinois, have invented a new and useful Improvement in Doorstops, of which the following is a full, clear, and exact description.

My invention relates to improvements in door stops, and it consists in the combinations, constructions, and arrangements herein described and claimed.

An object of my invention is to provide a door stop which will automatically lock a door in opened position.

15 A further object of my invention is to provide a device of the type described which can be readily attached to a door without altering the construction of the latter.

20 A further object of my invention is to provide a device of the type described which is simple in construction, inexpensive to manufacture, and efficient for the purpose intended.

25 Other objects and advantages will appear in the following specification, and the novel features of the invention will be particularly pointed out in the appended claims.

30 My invention is illustrated in the accompanying drawings, forming part of this application, in which—

Figure 1 is a plan view of the device as shown operatively applied to a door, the door being in opened position,

35 Figure 2 is a side elevation of the device, portions thereof being shown in section, and

Figure 3 is a plan view of the device as shown applied to a door, the door being in closed position.

40 In carrying out my invention, I provide a door 1 which is secured to a wall 2 by hinges 3. The wall 2 is reenforced by the ordinary means, such as a stud 4. The parts described so far are ordinary in construction and form no part of my invention, except in 45 so far as they cooperate with the parts to be described.

I then provide a bracket 5 which I secure to the door 1 by screws 6 and I also provide a bracket 7 which is secured to the stud 4 by 50 means of screws 8. As clearly shown in Figure 2, the brackets 5 and 7 are provided with lugs 9 and 10, respectively, the lugs being provided with alined vertical openings 11 and 12 therein. An arm 13 is provided with 55 a collar 14 at one end thereof, the collar being pivotally mounted between the lugs 9 by

means of a bolt 15 which is disposed in the alined openings 11 in the lugs 9 and in the bore 16 of the collar 14. In a like manner, I provide an arm 17 which is also provided 60 with a collar 18 at one end thereof, the collar being pivotally disposed between the lugs 10 of the bracket 7. A bolt 19 is disposed in the alined openings 12 of the lugs 10 and in the bore 20 of the collar 18. The arm 13 is provided 65 with a cup-shaped member 21 which has a square tapered recess 22 therein. The upper surface of the member 21 is also provided with an enlarged recess 23 which communicates with the recess 22. A pin 24 is 70 provided with a handle 25 and has its lower end 26 made square and tapering so as to be received within the recess 22. The pin 24 has a square recess 27 in the upper side 75 thereof and has a central bore 28 communicating with this recess. The free end of the arm 17 is provided with a downwardly projecting pin 29 which is made square for a portion of the length thereof adjacent the arm 17, such as at 30. The square portion 80 30 is adapted to be snugly received within the square recess 27 and the remainder of the pin 29 is adapted to be received within the bore 28.

From the foregoing description of the various parts of the device, the operation thereof may be readily understood. Assume that the door is in closed position and that the lower portion 26 of the pin 24 is not in alinement with the recess 22, but rides on the 90 lower surface of the recess 23. The door can now be opened and as it is swung about its hinges 3, the arms 13 and 17 swing with respect to each other, thus causing the lower portion 26 of the pin 24 to be brought into 95 alinement with the recess 22 when the door 1 is in opened position. The weight of the pin 24 will now cause the latter to drop into and to be received by the recess 22. It will therefore be apparent that the door 1 will be 100 held in opened position as long as desired, since the arms 13 and 17 are locked with respect to each other.

When the door 1 is desired to be closed, the pin 24 is manually lifted out of the recess 22 by means of the handle 25 as is shown in the dotted lines in Figure 2. The door 1 can now be swung into closed position, the lower portion 26 of the pin 24 being instantly thrown out of alinement with the 110 recess 22 and thus being permitted to ride freely on the lower surface of the recess 23.

It will thus be seen that I have provided a simple, effective, and easily operated means for locking the door 1 in opened position. The device consists of few parts and is not likely to easily get out of order.

A bolt 31 is centrally disposed in the pin 29 and projects slightly beyond the under side of the pin (see Figure 2). The pin 29, as will be seen, projects through an opening 32 in the member 21. A washer 33 and a nut 34 are disposed over the end of the bolt 31 and are carried thereby. The diameter of the washer 33 is slightly larger than the diameter of the opening 32 and thus secures 15 the pin 29 to the member 21.

This construction prevents the parts of the device from becoming disassembled during transportation.

I claim:

20 1. The combination with a support and a door hinged to said support, of an arm pivotally carried by the door and having a non-circular recess in the outer end thereof, a non-circular locking pin adapted to be received in the recess of said arm and being provided with a non-circular bore therein, and a second arm pivotally secured to said support and having a non-circular projection at the outer end thereof adapted to be 25 disposed in the bore of said pin, said pin being movable on said projection and adapted to be moved out of engagement with the recess of said first named arm.

25 2. The combination with a support and a door hinged to said support, of an arm pivotally carried by the door and having a non-circular recess in the outer end thereof, a non-circular locking pin adapted to be received in the recess of said arm and being provided with a non-circular bore therein, and a second arm pivotally secured to said support and having a non-circular projection at the outer end thereof adapted to be 30 disposed in the bore of said pin, said pin being movable on said projection and adapted to be moved out of engagement with the recess of said first named arm.

35 3. A device of the type described comprising an arm having a non-circular recess in one end thereof, a non-circular locking pin adapted to be received in the recess of said arm and being provided with a non-circular bore therein, and a second arm pivotally secured to said support and having a non-circular projection at one end thereof adapted to be 40 disposed in the bore of said pin, said pin being movable on said projection and adapted to be moved out of engagement with the recess of said first named arm.

4. A device of the type described comprising an arm having a non-circular recess in one end thereof, a non-circular locking pin adapted to be received in the recess of said arm and being provided with a non-circular bore therein, and a second arm pivotally secured to said support and having a non-circular projection at one end thereof adapted to be disposed in the bore of said pin, said pin being movable on said projection and being adapted to drop by gravity into the recess of said first named arm when said arms have been swung into a predetermined position.

5. A device of the type described comprising an arm having an opening in one end thereof, and a non-circular recess communicating with said opening, a second arm having a shank rotatably disposed in said opening, the shank having a non-circular portion, and a locking member slidably disposed on said shank and having a non-circular recess adapted to receive the non-circular portion of said shank, and having a non-circular outer surface adapted to be received in the non-circular recess of said first named arm.

6. The combination with a support and a door hinged to said support, of an arm having an opening in one end thereof, and a non-circular recess communicating with said opening, a second arm having a shank rotatably disposed in said opening, the shank having a non-circular portion, and a locking member slidably disposed on said shank and having a non-circular recess adapted to receive the non-circular portion of said shank, and having a non-circular outer surface adapted to be received in the non-circular recess of said first named arm.

7. A door stop comprising an arm, a second arm pivotally secured to said first named arm, and a gravity actuated locking member carried by said second named arm and being adapted to operatively engage with said first named arm when said arms have been swung into a predetermined position, whereby said arms are positively locked against further movement in either direction.

8. A door stop comprising an arm having a non-circular recess therein, a second arm pivotally secured to said first named arm, a gravity actuated member carried by said second named arm, said member having a non-circular portion adapted to enter said recess when said arm has been swung into a predetermined position, whereby said arms are positively locked against movement in either direction.

ARTHUR E. MOBERG.
